PROCESS AND MEANS FOR PRODUCING ALL WOOD PAPER,
APPLICATION FILED FEB. 16, 1917.

1,277,737.

Patented Sept. 3, 1918

UNITED STATES PATENT OFFICE.

ALBERT HENRY LEFEBVRE, OF WATERTOWN, NEW YORK.

PROCESS AND MEANS FOR PRODUCING ALL-WOOD PAPER.

1,277,737.

Specification of Letters Patent. Patented Sept. 3, 1918.

Application filed February 16, 1917. Serial No. 149,045.

To all whom it may concern:

Be it known that I, ALBERT HENRY LEFEBVRE, a citizen of the United States, residing at Watertown, in the county of Jefferson and State of New York, have invented a certain new and useful Process and Means for Producing All-Wood Paper, of which the following is a specification.

In the manufacture of paper from wood 10 disintegrated into its constituent fibers by processes that are mainly or wholly mechanical, it has been the practice, in order to secure a paper of proper texture and strength, to introduce into the mechanically 15 reduced fiber stock, through means of mixers that are more or less expensive to erect and operate, strengthening fibers obtained from various sources foreign to the wood, such as rags, for instance, which have themselves been already reduced by a much more 20 expensive process involving the use of chemicals.

I have discovered by extended research that there are in wood, as it comes from the 25 forest, all the materials necessary for making a strong and satisfactory paper without the addition of foreign materials; that the failure to produce such a paper from wood pulp heretofore, has resulted mainly from 30 the discarding of the stronger and more desirable fibers; that this discard has been due to lack of the proper method of utilizing the discarded materials; and that the discarded or rejected portion of the wood 35 has amounted to such a large percentage of the raw material as to work enormous waste.

I have further discovered by research that in the methods heretofore employed for 40 producing paper mainly from mechanically reduced wood, the waste, pollution of streams and use of bleaching chemicals can all be avoided by proper methods, and much of the expensive apparatus heretofore employed can be done away with by a proper 45 procedure. These considerations become additionally important when it is remembered that the use of chemicals is particularly destructive of the screens and other apparatus.

50 The present invention teaches a novel method of producing paper from wood with use of substantially all of the fibrous portions of the wood and through means of apparatus of a greatly simplified nature and 55 with great economy in materials and work

required; and it produces a new all-wood paper having superior strength and superior qualities, particularly in the matters of opaqueness and non-absorption of printing ink.

In the following disclosure, I shall refer to the article paper, and the process and means for producing same, because paper is the ultimate article to be produced, but it is to be understood that the distinguishing 60 characteristics which lend novelty to the article are present in the finished pulp stock as it issues from the screen, and the novel characteristics which distinguish the method of producing the stock, and the means for producing the same, relate to what takes place, at one stage or another, between the step of reducing the wood and forwarding the screened pulp to the forming apron of woven wire at the receiving end of the paper 65 machine. Therefore, except when the context otherwise indicates, a reference to pulp is to be understood as including paper made from the pulp, and vice versa, whether it goes to the paper machine, or merely passes 70 to the dehydrator, to form pulp for subsequent use in paper manufacture.

The underlying theory of the present invention is that everything which nature puts into the sustaining structure of the wood is 75 valuable as building material for incorporation into the structure of the paper to be made from the wood, and that the only portions of the tree that should be excluded 80 from the paper are the mere protecting parts, such as the bark and possibly a portion of the soluble binding materials which, in some wood, may be excessive for purposes 85 of paper-making, or which may exist in sufficient proportions to justify recovering 90 them as a by-product; and that it is only necessary to properly manipulate the disintegrated constituents of the tree structure to insure proper fabrication into a satisfactory 95 paper. This theory lends itself with peculiar 100 advantage to a procedure depending mainly or wholly upon mechanical steps for the reduction of the wood, because in such procedure as generally practised in the art, the reduced fibrous portions vary greatly in 105 length and strength, so that if properly distributed, the particles of greater length or strength become strengthening elements throughout the larger mass of shorter fibers, and make it unnecessary to add strengthen- 110

ing fibers from a foreign stock; moreover, in the disintegration of the wood, the longer or stronger parts resist reduction to their ultimate dimensions more than the shorter fibers, with the result that they break off in larger pieces and do not pass through the screens as promptly as the other, but pass over as tailings. In the methods heretofore practised, it has been customary to discard these tailings and pass them directly to the stream or waste outlet. I have found in practice that if these tailings be subjected to a further reduction treatment, they yield up the very elements of strength which the paper needs; that if they be passed to a means, which I shall herein call a refiner, subjecting them to a refinement or further reduction, and then delivered with the fresh stock coming in from the original grinder or reducer, and again passed over the screens, sufficient of this material of increased strength is mingled with the bulk of the stock to properly strengthen it; that there is much of the fine and valuable fiber which passes over with the tailings from the screen, due to its adhering to the unreduced material which would pass off with the latter, if discarded; and that if the tailings be continuously passed to the refiner, returned to the screens with the fresh stock, and rescreened, and this treatment be conducted in such manner that the secondary reduction or refinement is repeated for each particle until it is in condition to pass through the screen, distribution of the strengthening fibers is continuous and uniform; the total bulk of stock produced is increased not only by the refinement, but by saving the finer fibers adhering to the tailings or remaining suspended in the water which is used over and over again, and soluble binding materials may all be retained in the ultimate paper structure, unless special steps be taken to withdraw a portion thereof as already suggested.

While it is my belief that the larger particles which break off in the original reduction, contain stronger fibers, the success of my invention is not wholly dependent upon this condition, as it will be seen that the distribution of strengthening material throughout the stock may be due in greater or less measure to the fact that the secondary reduction or refinement, while conditioning the material to pass through the screen, does not get it to its ultimate fiber. In either instance, the strengthening material is present and it owes its distribution to the fact that it is produced by the secondary treatment and delivered constantly into the fresh stock from the grinder, and it adds to the output of the plant and reduces the cost of production by saving to the stock what formerly was discarded, while it further cheapens the cost of production of a satis-

factory paper stock by substituting these waste materials for foreign fibers heretofore used.

From the foregoing, it will be seen that—

One feature of the present invention consists in an all-wood or substantially all-wood paper composed mainly of the finer fibrous constituents of the wood structure, but having the stronger or coarser constituents of the wood uniformly distributed 75 throughout the paper structure and constituting a strengthening filler therefor.

Another feature consists in the production of paper from wood by disintegrating the wood into substantially fibrous condition 80 with stronger or coarser particles of the wood intermingled with the finer, screening out the coarser material, passing it to a refiner for further reduction, delivering the refined material with the fresh incoming 85 stock of reduced material, and passing them collectively to the screen, and so on in continuous operation; subordinate features under this part of the invention consisting in passing both the partially refined 90 and sufficiently refined products of the refiner into the incoming stock, utilizing the same water as the vehicle for the materials in passing them from stage to stage in the process, and dividing up the screen into successive sections over which the material to be screened passes in succession, preferably with a settling riffle for the coarser material at the end of each section, and with the screenings from all the sections passing into 95 a common passageway to the dehydrator, paper machine or other place of use of the pulp. Another feature of the invention subordinate to the general idea of continued circulation and repeated screening of coarser 100 material in the presence of fresh material and with repeated refinement of the coarse material, relates to the treatment of the fresh material and added product of the refiner in its passage to the screens, according to 105 which feature, the stock is floated through an elongated scrubber or scrubbing tanks having a series of compartments through 110 which it successively passes by cascading over the dividing walls between the compartments and from which it escapes into a tank which is of sufficiently larger area to permit it to 115 spread out and suddenly lose its speed of travel, so that the heavier portions settle or assume a lower stratum, and from this settling chamber, passing it by means of a gentle pumping action upward through a hydrostatic gravity separator whence it escapes 120 at the top and passes directly to the screens. The scrubbing tanks afford opportunity for 125 detachment of bark, sand and other foreign matter; the settling tank affords an opportunity for much of this bark and foreign material to precipitate, and the hydrostatic gravity separator through which there is a 130

gentle upward current of fluid, completes the separation, so that the stock emitted at the top of the stack is sufficiently purified to insure production of a paper of satisfactory color without the addition of chemicals. If desired, a suitable proportion of alum may be thrown into the scrubbing tanks or settling tank to assist the dirt to precipitate, but this will not be necessary in all cases, 10 although when added, it can be used with greatest economy, since the same water is being circulated indefinitely through the system.

A third feature consists in the apparatus 15 employed for carrying out the process above outlined and producing the new paper described. This consists essentially in a primary reducer, preferably in the form of a grinder; a secondary reducer or refiner, 20 which may be of any one of a number of different machines, but which is preferably an ordinary Jordan engine, which delivers into the same channel as the primary reducer, so that the refined material is systematically mingled with the product of the 25 grinder; an elongated scrubbing tank through which the material is floated from end to end, but which is divided by transverse partitions into a number of pockets 30 through which the material successively flows from one to another by cascading over the partition walls; a settling chamber which is preferably a number of times larger in area than the sectional area of the scrubbing tank, and into which the material may 35 be spread out and lose its momentum, so as to favor settling of foreign matters; a hydrostatic gravity separator in the form of a stand-pipe, preferably of much less horizontal area than the settling tank, but rising 40 vertically a distance sufficient to afford ample opportunity for complete separation of the stock that is already conditioned or is to be passed over the screens to the refiner; 45 and finally, the screens to which the material is delivered directly from the stand-pipe and which preferably comprise a longitudinal series of screening sections arranged in the form of riffle plates having settling 50 pockets between them with outlets for passed material, delivering preferably to a common escape passage and with a tailing passage leading to the refiner. Obviously, by 55 passing the water, with its burden of material in suspension, successively over a series of plates, the proportion of water as the vehicle, to the fibrous material which it carries, will gradually reduce toward the tailing end, and there may be some difference 60 in the character of the fiber passing through the different sections. By delivering the tailings from all the sections into a common passageway, a sufficient mixture 65 will be insured to produce a homogeneous stock.

As has been stated, the water which serves as a vehicle and also for softening the fiber and dissolving the binding materials, is circulated repeatedly through the system. There will, of course, be constant loss of 70 water that goes out with the finished fiber, either in the form of matted pulp stock or as the sheet upon the forming apron of the paper machine, and to this extent, the supply of water will be continuously replenished. 75 This may be conveniently done by delivering fresh water at the surface of the grinder, or fresh water with a part of the water already in circulation. A constant flow of water at this point is necessary, in order to 80 keep down the heat resulting from the friction of grinding, which should not be allowed to go above 170° F. to avoid curling the fiber. Otherwise heat is conserved as far as practicable, as it makes for economy 85 in that it favors the solution of the binding materials and economizes in heat required for drying the paper web when it reaches the felts in the paper machine.

An illustrative apparatus embodying one 90 part of the present invention and capable of operating for carrying out the method which constitutes another part of the invention in the production of paper, which constitutes a third part of the invention, is 95 shown schematically in the accompanying drawing.

In said drawing, 1 represents a wood grinder discharging its product at 2, whence it is conveyed by the water, also delivered 100 at this point, into the scrubbing tank 3, divided by partitions 3^a into a number of successive scrubbing chambers through which the liquid passes successively by cascading over said partitions. 4 represents a 105 settling tank having a much larger capacity than the sectional area of the scrubbing tank, in which the fluid can lose its momentum so as to favor precipitation of foreign matter remaining in suspension. 5 is a 110 stand-pipe rising upwardly a considerable distance above the settling tank 4 (about 12 feet in height will be found effective), and into this stand-pipe the fluid is forced by means of the rotary pump 5^a, driven by shaft 115 5^b, or otherwise as may be convenient, so as to maintain in the stand-pipe a hydrostatic gravity separator. The capacity of the pump 5^a is just sufficient to keep up gentle progress of the fluid upward through 120 the stand pipe 5 and cause it to overflow at the brim 5^c, whence it passes to the screens 6. The screens are made up of a number of sections 6^a, each having a suitable collector 6^b for the material passing therethrough 125 and being separated from the ensuing screen by a riffle or settling depression 6^c. The screens thus formed will be made up of the conventional metal plates with longitudinal slots of such width as will pass fiber of the 130

desired fineness. The several collectors 6^b are made to discharge into the common passageway 6^a, whence the finished pulp escapes and is conducted for the use to which it is to be put. The tailings from the screen 6 will be made up of such coarsely reduced particles of wood as cannot pass through the screens and which escape, naturally, over the lower end of the screen, together with material which lodges in the riffles 6^c, which is also coarse, water-logged, and heavy, and which will be washed out from the riffles periodically by application of a hose or stream of water temporarily applied from an extraneous source, or forced from some point in the circulatory system. These tailings pass through tail-pipe 6^e to the secondary reducer or refiner 7, where they are further reduced and delivered through a discharge pipe 7^a into the receiver 2 for the incoming new stock that is being produced by the grinder 1, and here the refined tailings mix with the new stock, pass through the scrubbing tank 3, settling chamber 4, hydrostatic gravity separator 5, and again reach the screens 6, where more of their fibrous constituency passes through the screens. The still unreduced or insufficiently refined parts, whether they have once been through the refiner, or come for the first time from the grinder, pass into the tailing-pipe 6^e and to the refiner 7, and thence to the receiving point for new stock just as before. This process is kept up continuously on the theory that there is no part of the wood that will not ultimately, by repeated treatment and after sufficient soaking, be reduced sufficiently to enter into the paper stock. The refiner 7 delivers the fiber in a condition somewhat different from that of the fiber which comes from the grinder. That is to say, it is either made up of longer fibers or of fiber groups that are of greater dimensions and strength, yet sufficiently reduced to enter satisfactorily into the paper structure. A very satisfactory form of apparatus to be used for the refiner 7 is a well-known Jordan engine, employing two closely acting concentric cones. Cooling water for the grinder may be conveniently supplied by the pipe 8, which may lead from any convenient source, as for instance from the pipe 9^a leading from the machine 9 (either dehydrater or paper former) which utilizes the finished stock.

It is to be understood that this part of the invention is not restricted to the precise apparatus herein shown, or to the particular construction of parts which go to make up such apparatus, so long as they are capable of performing the several functions ascribed

to them and arranged in a system substantially as set forth.

I claim:

1. In the process of manufacturing paper, the steps which consists in reducing wood to produce finely divided fibrous material and partially reduced portions; passing the material collectively through a scrubbing tank; then separating foreign matters by the action of gravity; then screening; then refining the screen-rejected parts to produce relatively coarse fibrous material; delivering the refined parts with the incoming stock of the original reduction, and again circulating the material collectively through the scrubbing tank and separating means and over the screens, and so on in continuous operation.

2. In a paper-making apparatus, the combination of a primary reducing means for reducing wood into fine fibrous material and partly reduced material; means for refining the partly reduced material, delivering its output to the material issuing from the primary reducing means; a scrubbing tank for treatment of all the material, a hydrostatic gravity separator receiving the material after treatment in the scrubbing tank, screens for treating the material after passing through the separator, and a tailing-pipe leading from the screen to the refiner.

3. In a paper making apparatus for making paper from structurally differing parts of wood comprising a primary reducer, a refiner, and an endless hydraulic circulatory system including the discharges from the reducer and refiner, a scrubber, and a screen, the tailings discharge of the screen being connected to the refiner.

4. In a paper making apparatus for making paper from structurally differing parts of wood comprising a primary reducer, a refiner, and an endless hydraulic circulatory system including the discharges from the reducer and refiner, a scrubber, a settling chamber, and a screen, the tailings discharge of the screen being connected to the refiner.

5. In a paper making apparatus for making paper from structurally differing parts of wood comprising a primary reducer, a refiner, and an endless hydraulic circulatory system including the discharges from the reducer and refiner, a scrubbing tank, a settling chamber, and a hydrostatic gravity separator, and a screen, the tailings discharge of the screen being connected to the refiner.

The foregoing specification signed at Watertown, New York, this 9th day of February, 1917.

ALBERT HENRY LEFEBVRE.
